[57] CLAIM

The ornamental design for a lawn and garden weeder, as shown and described.

DESCRIPTION

FIG. 1 is a perspective view of a lawn and garden weeder showing my new design, with the broken line included for illustrative purposes forming no part of the claimed design; FIG. 2 is a top view of the lawn and garden weeder; FIG. 3 is a rear view of the lawn and garden weeder; FIG. 4 is a right side view of the lawn and garden weeder, the left side of the weeder being a mirror image of the right side thereof; FIG. 5 is a front view of the lawn and garden weeder; FIG. 6 is a bottom view of the lawn and garden weeder; and, FIG. 7 is an enlarged view of the weeder taken along the line 7—7 in FIG. 3.
